[57] CLAIM

The ornamental design for a digital display pager, as
shown and described.

DESCRIPTION

FIG. 1 is a front elevational view of a digital display pager showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and

FIG. 7 is a front, top and left side perspective view
thereof.

The broken line showing of digital data displayed in
FIG. 7 is for illustrative purposes only and forms no
part of the claimed design.

FIG. 1

FIG. 2

FIG. 3

FIG. 4

FIG. 5

FIG. 6

FIG. 7
